COMBINED HOUSING CARRYING CASE FOR A HAIR DRYER

Robert S. Waters, Lancaster, Edward J. Doyle, Hatboro, and Meyric K. Rogers, Lancaster, Pa., and Nial C. Bartram, Wilmington, Del., assignors to Schick Incorporated, Lancaster, Pa.

Filed Feb. 22, 1973, Ser. No. 334,680

Term of patent 14 years

Int. Cl. D28—03

U.S. Cl. D86—10 F

7-10-2-

FIG. 1

FIG. 2

FIG. 3

FIG. 1 is a perspective view of a combined housing and carrying case for a hair dryer showing our new design.

FIG. 2 is a top plan view of the combined housing and carrying case for a hair dryer shown in FIG. 1.

FIG. 3 is a right side elevational view of the combined housing and carrying case for a hair dryer shown in FIG. 1.

FIG. 4 is a front elevational view.

FIG. 5 is a rear elevational view.

FIG. 6 is a bottom plan view.

The left side elevational view of the combined housing and carrying case for a hair dryer is a mirror image of the right side elevational view shown in FIG. 3.

We claim:

The ornamental design for a combined housing and carrying case for a hair dryer, as shown and described.
